UNITED STATES PATENT OFFICE

127,312

DESIGN FOR A BOWL OR SIMILAR ARTICLE

Carl Schmitz, New York, N. Y., assignor to Verlys of America, Inc., New York, N. Y., a corporation of New York

Application March 11, 1941, Serial No. 99,498

Term of patent 7 years

To all whom it may concern:

Be it known that I, Carl Schmitz, a citizen of the United States of America and a resident of New York, in the county of New York and State of New York, have invented a new, original, and ornamental Design for a Bowl or Similar Article, of which the following is a specification, reference being had to the accompanying drawing, forming a part thereof.

Figure 1 is a top plan view of a bowl or similar article, showing my new design. Figure 2 is a side elevational view of the same.

I claim:

The ornamental design for a bowl or similar article, as shown.

CARL SCHMITZ.
